Application October 5, 1950, Serial No. 188,519

4 Claims. (Cl. 313—107)

1

This invention relates to electric discharge tubes comprising a cathode activated by one or more alkaline earth metal oxides.

It is known that, in electric discharge tubes, the grids and possibly also the anode of a tube may tend to emit electrons thermally. This is because the grids are heated by the cathode and, probably also from the anode, while the anode itself is heated by the anode current and because alkaline earth metal and/or oxide evaporated from the cathode produce an electron-emitting layer on the grids and the anode. To prevent the primary emission thus produced, it is known to coat the grids with a thin layer of gold. This has the disadvantage that gold is comparatively volatile so that it readily evaporates and in consequence the grids may tend to emit thermally and the cathode may be poisoned. Moreover the use of gold is comparatively expensive.

The object of the present invention is to provide an alternative and improved means for preventing such primary emission in tubes having a cathode activated by alkaline earth metal oxides.

According to the invention, a tube comprises a cathode activated by alkaline earth metal oxides, and has at least one grid and/or the anode consisting at the surface of a thin layer of thorium in the non-oxidised condition.

It has been found that in tubes according to the invention, the grids have approximately the same low thermal grid-emission as in tubes in which the grids are coated with gold.

In order to reduce the electron-emission of anodes, it is known to coat them with thorium in an oxidised condition. However, the electron-emission is not prevented to a sufficient degree by this means upon vaporization of barium from the cathode.

In tubes having a tungsten-thorium cathode, it is furthermore known to coat a water-cooled anode with a layer of porous thorium with a view to binding as much as possible any gases set free in the tube. In this type of tube however,

2

the need for the invention is not present due to the absence of alkaline earth metal oxides.

In the drawing 1 designates an evacuated glass tube, 2 is an oxide coated spiralised cathode, 3 is the grid and 4 the anode. On the grid bars and the anode surface is sintered a layer of thorium powder 5, respectively 6, if preferred in an atmosphere of hydrogen. The thorium may also be applied by evaporating it to the grid and anode in a special vessel.

What I claim is:

1. An electric discharge tube comprising a cathode activated with alkaline earth metal oxides, and an electrode having a thin surface layer of non-oxidized thorium to suppress thermal electron emission therefrom.
2. An electric discharge tube comprising a cathode activated with alkaline earth metal oxides, a grid, and an anode having a thin surface layer of non-oxidized thorium to suppress thermal electron emission from the anode.
3. An electron discharge tube comprising a cathode activated with alkaline earth metal oxides, a grid having a thin surface layer of non-oxidized thorium to suppress thermal electron emission therefrom, and an anode.
4. An electron discharge tube comprising a cathode activated with alkaline earth metal oxides, a grid having a thin surface coating of non-oxidized thorium, and an anode having a thin surface coating of non-oxidized thorium, said thorium coatings suppressing thermal electron emission from said grid and anode electrodes.
